FEEDING MECHANISM FOR BOX BLANK
MACHINESKarl Sieg, Philadelphia, Pa., assignor to Samuel
M. Langston Co., a corporation of New Jersey

Application June 22, 1939, Serial No. 280,433

14 Claims. (Cl. 93—58.2)

This invention involves certain improvements in feeding mechanism for delivering comparatively stiff sheets, such for instance as corrugated boards, in succession from a stack or pile to mechanism for printing, scoring, slotting or otherwise operating upon the sheets.

In machines for making box blanks and feeding a separate sheet for every revolution of the printing cylinder or slotting head, the maximum length of sheet that can be properly operated upon is substantially equal to the circumference of the head or cylinder operating on the sheet. If the length of the sheet exceeds to a limited extent the periphery of the operating head, it is necessary to feed one sheet for each alternate revolution of the head or cylinder. In either case, the feeding device takes the sheet from the pile and advances it to the feed rolls at such a rate that the speed of the sheet at the instant the forward edge is gripped by the feed rollers should equal the peripheral speed of said rollers, so that there will be no bending of the sheet or mutilation of the edge.

One object of the present invention is to provide a power transmission mechanism of the general type above referred to, having means for changing the frequency of the cycles of operation of the feeding mechanism, without changing the speed of said mechanism at the instant the forward edge of the advancing sheet is gripped by the feed rollers.

By means of this transmission mechanism, the frequency of the cycles of operation of the feeding mechanism can be changed at will to feed a sheet for every revolution or every alternate revolution of the slotting head or printing cylinder, depending upon the length of the blank being fed. This change in frequency is also advantageous in those cases where there are heavy ink spreads, since a greater amount of ink is made available through the standard ink distributing rolls by virtue of the fact that ink is taken on at each revolution of the printing cylinder, but is applied to a sheet only every other revolution.

Various other objects, features and advantages of the invention will be apparent from the following particular description, and from an inspection of the accompanying drawings, in which:

Fig. 1 is a diagrammatic side elevation of a printer slotter shown with one form of drive for the sheet feeding mechanism, embodying the present invention.

Fig. 2 is a diagrammatic side elevation showing the feeding of sheets successively through the

field of action of the operating head, with the power transmission mechanism set to feed one sheet per revolution of said head.

Fig. 3 is a diagrammatic side elevation showing the feeding of sheets through the field of action of the head, when the power transmission mechanism is set to feed one sheet for every two revolutions of said head.

Fig. 4 is a diagram showing the velocity of the feeding mechanism at different stroke positions, with the power transmission mechanism set to feed one sheet per revolution of the operating head.

Fig. 5 is a diagram showing the velocity of the feeding mechanism at different stroke positions, with the power transmission mechanism set to feed one sheet for every two revolutions of the head.

Fig. 6 is a side elevation of the power transmission mechanism shown in Fig. 1, certain parts being broken away and certain parts being shown in section.

Fig. 7 is a section taken on line 7—7 of Fig. 6, but showing the speed change gearing of the power transmission mechanism in neutral position.

Fig. 8 is a top plan view of the transmission mechanism of Figs. 6 and 7, but on a smaller scale.

Fig. 9 is a diagrammatic view showing the position of certain gears of the transmission mechanism of Figs. 1, and 6 to 8, when the speed of the output shaft of said mechanism is at its maximum.

Fig. 10 is a view similar to Fig. 9, but showing the position of the same gears of the transmission mechanism after the input shaft of said mechanism has rotated one revolution from the position shown in Fig. 9.

Figs. 11, 12 and 13 are horizontal sections, somewhat diagrammatically showing other forms of power transmission mechanisms which may be employed in carrying out the present invention, certain parts of said mechanisms being shown in top plan view.

Fig. 14 is a horizontal section through another form of power transmission mechanism which may be employed.

Fig. 15 is a section taken on line 15—15 of Fig. 14.

Fig. 16 is a horizontal section through another form of power transmission mechanism which may be employed, and

Fig. 17 is a section taken on line 17—17 of Fig. 16.

In the specific form of machine shown in Fig. 1, which has been selected for purposes of illustration, and to which the invention may be applied, there is provided the usual frame structure 5 (not shown), which carries a feed table 10 upon which may be stacked a plurality of superposed relatively stiff sheets between guide members 11, and between a pair of brackets 12 and 13, one being disposed at the front end and the other 10 at the rear. The rear bracket 13 is adjustable lengthwise of the table 10 in accordance with the length of the sheets to be fed, and the guides 11 laterally in accordance with the width of the sheets. There may be as many of these front 15 and rear brackets 12 and 13 as may be desired depending upon the width of the sheets being fed.

The sheets are fed successively into the field of action of the machine by a feed mechanism, which includes a reciprocating bar 14, guided 20 in a groove in the table 10, so as to move back and forth in the direction in which the sheets are to be fed. This bar 14 may be actuated by any suitable means, as for instance an oscillating lever 15, fixed to a rocker shaft 16, to which 25 is affixed another lever 17 connected to a slide 18 on the feed bar 14 by means of a link 20. The lever 15 is connected to one end of a connecting rod 21, the other end being operated by a power transmission mechanism, which embodies 30 the present invention, and which will be hereinafter described.

The feed bar 14 has one or more feeding members or knockers 23, rigidly connected thereto, but adjustable along the length thereof in accordance 35 with the length of the sheets to be operated on. The feed knocker 23 has a shoulder member 24, positioned to engage the rear edge of the bottom sheet during its forward movement. When the shoulder member 24 40 of the knockers reach a position rearwardly of the rear edge of the stacked sheets, the bottom sheet will drop, so that on the next forward stroke of the knocker 23, said shoulder member 24 will engage the rear edge of said lowermost 45 sheet, and will move said sheet forwardly.

The feeding mechanism per se so far described forms no part of the present invention, and may be of any suitable form such as that shown in the Moritz Patent No. 1,797,692, the Sieg Patent 50 No. 1,644,695, or the Langston Patent No. 1,150,210. The details of this feed construction are therefore omitted for the sake of simplicity.

The feeding mechanism delivers the sheets successively to a suitable printer slotter, which 55 in the form shown includes a first pair of feed rolls 28 and 29, and two pairs of printing units separated by two pairs of feed rolls 30 and 31. Each of these printing units includes a lower pressure cylinder 32, and an upper printing cylinder 33 carrying a type plate, which is inked by a series of ink fountain rolls (not shown). Different inks are supplied to the type plates of different printing cylinders, and the type plates and cylinders may be so positioned that, as the 60 cylinders operate in succession, the two printings will be in the desired registry.

The sheets that have been printed pass through a scorer 35, and then through a slotter, including upper and lower slotting heads of suitable 70 design such as that shown in the Langston Patent No. 1,769,883, in which a lower slotting head 36, having an annular groove, cooperates with an upper slotting head 37, carrying a pair of knives 38 relatively adjustable circumferentially 75 of said head 37, to vary the distance therebe-

tween, and thus control the length of the unslotted portion of the blank between the ends of the slot extending in from opposite edges. The upper slotting head 37 is of the same diameter as that of the upper printing cylinders 33. 5

All of the rotatable parts of the printer slotter which contact with the travelling sheets are operated at the same peripheral speed as the speed of the advancing sheets. A train of gears is shown in dot and dash lines, and receiving power 10 from a drive shaft 40.

Fig. 2 shows two successive sheets A and B advancing through the machine after the slots at the forward end of the sheet A have been completed, and while the slots at the other end 15 are in the process of being formed, the sheet feeding power transmission mechanism being set to feed one sheet for every revolution of the slotting heads 37. With this setting of the transmission mechanism, each slotting head 37 carries two 20 knives 38, the peripheral distance X therebetween being equal to the length of the unslotted portions of the sheet, and the maximum length of sheet that can be operated upon will be equal to the circumference of said heads. When slotting such maximum length sheets, the knives 38 will be close together substantially as shown in Fig. 1, and the sheets will be fed close together almost in end to end contact.

As a feature of the present invention, a power 25 transmission mechanism is provided for the sheet feeding, by means of which the total time cycle of the feeding mechanism may be changed without changing the speed of travel of the sheets through the machine, to permit operations on 30 longer sheets or to slow down the feeding of the sheets to permit heavy ink spreads thereon. For that purpose, the power transmission mechanism is constructed, so that irrespective of the time cycle of the feed mechanism, said feed mechanism 35 will have a maximum speed at the portion of its forward stroke when the forward edge of the sheet being fed is first gripped between the first pair of feed rolls 28 and 29 as shown in Fig. 1. Since the forward edges of the stacked 40 sheets are usually maintained at the same distance from these feed rolls 28 and 29, as determined by the position of the front bracket 12, regardless of the length of the sheets, this maximum speed must occur in the same position of the 45 feed slide 18 shown in Fig. 1, irrespective of any changes in the time cycle of said slide.

In Figs. 1, and 6 to 10 is shown one form of sheet feeding power transmission mechanism, which may be used to accomplish this function, 55 and which includes an input shaft 50 driven from the drive shaft 40 through intermeshing spur gears 51 and 52, and at the same angular speed as that of the printing cylinders 33 and the slotting heads 37, so that said cylinders and 60 said heads will rotate one revolution for every revolution of the input shaft 50.

The mechanism also includes an output shaft 53, parallel to the input shaft 50, and a first variable speed ratio unit between said shafts, 65 shown as a pair of intermeshing elliptical gears 54 and 55, having their major and minor radii in the ratio of 2:1. With this transmission means, while the input shaft 50, printing cylinders 33 and slotting heads 37 rotate through one revolution at a constant speed, the output shaft 53 will rotate through one revolution but at a variable speed, and will have a given maximum angular velocity at the phase or portion of the cycle 70 shown in Figs. 1, 7 and 9.

Affixed to the output shaft 53 is a crank 56, which is connected to one end of the connecting rod 21 of the feeding mechanism in such angular position, that when said output shaft is at its maximum velocity phase shown in Figs. 1, 7 and 9, the feed slide 18 will be traveling at a maximum velocity equal to the peripheral velocity of the feed rolls 28 and 29, and will be in that position of its forward stroke at which the forward end of the sheet being fed is at the nip portion of said feed rolls. During the remainder of the forward stroke of the feed slide 18, the feeding of this sheet through the machine will be accomplished by the rotating feed parts of said machine.

Since the feed slide 18 will effect a complete stroke for every revolution of the output shaft 53, and since said shaft rotates at the same frequency or at the same total time cycle as that of the printing cylinders 33 and slotting heads 37, the feeding mechanism will feed one sheet per revolution of said cylinders and said heads.

A speed change gearing is provided for changing the total time cycle of the feeding mechanism with respect to the printing cylinders and slotting heads. In the form shown, this gearing includes a pair of intermeshing circular reduction spur gears 57 and 58, in series with elliptical gears 54 and 55, and having a 2:1 speed ratio. These gears 57 and 58 if used alone would reduce the maximum speed of the output shaft 53 one-half at the phase thereof shown in Fig. 9, if no compensating means be provided.

In order to neutralize the effect of the reduction gears 57 and 58 on the maximum speed of the output shaft 53, there is provided a second variable speed ratio unit shown as a pair of intermeshing elliptical gears 60 and 61 in series with the first pair of elliptical gears 54 and 55, and having their major and minor radii in the ratio of 2:1. When the drive is through both pairs of elliptical gears and the reduction gears 57 and 58, the output shaft 53 will be driven at one-half the frequency or total time cycle of the input shaft 50. However, the pair of elliptical gears 60 and 61 is arranged to correspond in position with the elliptical gears 54 and 55 in the portion of the cycle shown in Fig. 9, so that the maximum velocity of the output shaft 53 will be the same in this portion regardless of the setting of the speed change gearing.

The elliptical gear 54 is fixed to the shaft 50, while the elliptical gear 55 is so mounted that it can be coupled to or uncoupled from the output shaft 53. The smaller speed change gear 57 is rigid with the elliptical gear 55 and a sleeve 62, and encircles the output shaft 53. The larger speed change gear 58 encircles the shaft 50, and is rigid with a sleeve 63 and the elliptical gear 60. The other elliptical gear 61 encircles the shaft 53.

The means for connecting the two shafts 50 and 53 through either the first or the second transmission means includes a sleeve 64 keyed on the shaft 53, and adapted to interlock with teeth 66 on the sleeve 62 or teeth 67 on the elliptical gear 61.

When the clutch sleeve 64 engages the clutch teeth 66, the power is transmitted from the shaft 50 to the shaft 53 through the elliptical gears 54 and 55 and the clutch. When the clutch sleeve 64 engages the other clutch teeth 67, the power is transmitted from the shaft 50 to the shaft 53 through the gears 54, 55, sleeve 62,

gears 57, 58, sleeve 63, gears 60 and 61, and the clutch.

The axial shifting of the sleeve 64 into the desired speed change setting may be accomplished by any suitable means. As shown, there is employed a handle 70, connected to a pivot shaft 71, journalled on a frame plate 72 on the upper side of the transmission housing 73. Fixed to this pivot shaft 71 is a bracket or arm 74 carrying a yoke 75, extending in a peripheral groove 76 of the sleeve 64. Connected to one end of the handle 70 is a spring-pressed locking pin 77, adapted to extend into either one of two holes 78 to determine the extreme axial positions of the sleeve 64 in coupling engagement with the clutch teeth 66 or 67, and to hold said sleeve in either of said positions.

When the power transmission mechanism is in position shown in Fig. 9 with the major axes of the first pair of elliptical gears 54 and 55 in alignment, the second pair of elliptical gears 60 and 61 will be in corresponding position, regardless of whether or not the first or the second transmission means is coupled between the two shafts 50 and 53. In this position of the elliptical gears, the feed slide 18 will travel at maximum velocity in the position of its forward stroke shown in Fig. 1. In any other position of the feed slide 18, the angular position of the first pair of elliptical gears 54 and 55 will depend upon whether or not one or the other of the power transmission means is coupled between the two shafts 50 and 53. It is therefore essential, in order to maintain a predetermined relationship between the position of the feed slide 18 and the angular position of the elliptical gears, that the gear shifting be effected when the feed slide 18 is in the same predetermined position, for instance that shown in Figs. 1, 6, 7 and 9.

For indicating this predetermined stopping position for the transmission mechanism, there may be employed flange plates 80, secured to the ends of the shafts 50 and 53 respectively for rotation therewith, and carrying indication marks 81 on their peripheries cooperating with pointers 82 secured to the housing 73. The indication marks 81 are so positioned, that when both of them are in registry with their respective pointers 82, both pairs of elliptical gears will be in the same phase shown in Fig. 9, and the crank 56 will be in the maximum velocity position shown in Fig. 1.

In the operation of the mechanism, when the coupling sleeve 64 is in engagement with the clutch teeth 66 for a 1:1 frequency transmission, the output shaft 53 will be driven at a variable speed and the feed slide 18 will be driven at a variable speed as indicated by the curve in Fig. 4. In this curve, the ordinates D indicate the linear speed of the feed slide 18, at a corresponding stroke position, and the interval between said ordinates represents $\frac{1}{26}$ of a revolution of the input shaft 50, printing cylinder 33, and slotting heads 37, so that the curve indicates the speed of the feed slide 18 at any position of its stroke, and the corresponding phase position of said printing cylinders and said slotting heads. The ordinate D' corresponds to the position shown in Fig. 1, at which the feed slide 18 will reach its maximum velocity, equal to the peripheral velocity of the feed rolls, in which position the forward edge of the sheet will be substantially at the nip portion of the feed rolls 28 and 29.

When the coupling sleeve 64 is in engagement with the clutch teeth 67, the drive will be through

the second transmission, and the shaft 53 will be driven at a variable speed to make one revolution for every two revolutions of the input shaft 50. When the elliptical gears 54 and 55 reach the 5 position shown in Fig. 9, the second pair of elliptical gears will be in corresponding position, so that the angular velocity of the output shaft 53 in this phase position of the gears will be the same as it was when driving through the first 10 transmission means. At the end of one revolution of the input shaft 50, the elliptical gears 54 and 55 will be in the position shown in Figs. 9 and 10, while the elliptical gears 60 and 61 will be in exactly the reverse position as shown in Fig. 10, 15 so that the speed of the output shaft 53 will be materially less than that in the 1:1 setting of the speed change gearing. At the end of the second revolution of the input shaft 53, the two sets of elliptical gears will again be in the position shown 20 in Fig. 9, and the output shaft 53 will then again reach the same maximum velocity attained by the transmission in the 1:1 gear setting.

In Fig. 5 is shown a curve, which is similar to the curve of Fig. 4, except that it applies to the 25 1:2 transmission, and which indicates that the feed slide 18 makes one complete stroke for every two revolutions of the input shaft 50, and the maximum velocity D' of the feed slide 18 occurs in the same position of its forward stroke, and is 30 equal to the maximum velocity attained by the feed slide when running on a 1:1 speed ratio. Thus there will be one point in the cycle of movement of the feed slide 18, where the maximum linear velocity will be the same irrespective 35 of whether the clutch be in one position or the other. In one case, this point is reached once in each revolution of the printing cylinders 33 or the slotting heads 34, and in the other case, it is reached once in each two revolutions of these 40 members.

With the feed of one sheet in every two revolutions of the printing cylinders and slotting heads, a sheet longer than the circumference of said members can be properly operated on. In Fig. 3 45 is shown the operation of the slotting head on successive sheets A' and B' with a 1:2 setting of the speed change gearing. With this setting, one of the knives 38 is removed, so that the same knife 38 operates to form the slots on both ends 50 of each sheet, and the maximum length of the sheets that can be operated on is equal to the circumference of the slotting head plus the circumferential length of the knife.

Instead of using elliptical gears, any other 55 equivalent means may be employed for imparting variable angular velocity to the output shaft, and for maintaining the same linear velocity of the feed mechanism at a portion of the cycle thereof irrespective of changes in its total time cycle. 60 For instance, I may employ for that purpose other shapes of non-circular gears, eccentric slide cranks, Geneva gears, or the like.

Fig. 11 shows another form of sheet feeding power transmission, comprising the input shaft 65 50, driven from the drive shaft 40 by suitable gearings as in the construction of Figs. 1 to 10, to rotate said input shaft at the same constant angular speed as that of the slotting heads, and two parallel output shafts 53a and 53b, each carrying a crank 56 for selectively operating a connecting rod 21 to the reciprocating feed mechanism. Between shafts 50 and 53a is a first variable speed ratio unit in the form of an eccentric slide crank, comprising a slotted crank disc 90, 70 fixed to the end of the input shaft 50, and a crank 75

arm 91 fixed to the opposed end of the shaft 53a, and carrying a crank wrist roller 92, slideable in the slot of said disc.

Parallel to the output shaft 53a is a shaft 93, 5 driven from said output shaft by intermeshing reduction spur gears 94 and 95, having a speed ratio of 2:1, so that said shaft 93 will rotate one-half revolution for every revolution of said output shaft. Between the shafts 93 and 53b is a second variable speed ratio unit in the form of an eccentric slide crank, comprising a slotted disc 96 10 fixed for rotation with the gear 95, and a crank arm 97 fixed to the end of the shaft 53b, and having a crank wrist roller connection in the 15 slot of said disc.

The first slide crank 90, 91 has a suitable speed ratio at the maximum velocity phase of the crank arm 91, to impart the desired maximum angular velocity to the output shaft 53a and in turn to the reciprocating feed mechanism. A suitable 20 speed ratio between the inlet and outlet side of this first slide crank in this maximum velocity phase may be 1 to 1.76, and of the second slide crank 96, 97 in this phase 1 to 2 to neutralize the effect of the reduction gears 94 and 95. The two 25 output shafts 53a and 53b will therefore rotate at the same maximum angular speed at the same portion of their cycle, but shaft 53b will rotate one-half revolution at variable speed for every one revolution of the input shaft 50, while output 30 shaft 53a will rotate one revolution at variable speed for every one revolution of said input shaft.

The feed mechanism is therefore coupled selectively to either one of the output shafts 53a or 35 53b by a connecting rod according to the desired 30 total time cycle of said feed mechanism, the maximum speed of said feed mechanism at the portion of its stroke shown in Fig. 1 being the same with either connection.

Fig. 12 shows another form of sheet feeding 40 transmission mechanism, comprising the input shaft 50, output shaft 53, and three shafts 100, 101 and 102 parallel to said input and output shafts. Between the two shafts 50 and 100 is a speed change gearing including two pairs of 4 intermeshing gears, one pair comprising gears 103 and 104 in a 1 to 1 speed ratio, the other pair comprising gears 105 and 106 having a 2 to 1 speed ratio. The gears 103 and 105 are fixed to the input shaft 50, while gears 104 and 106 are 5 loosely mounted on the shaft 100, but selectively coupled thereto by a slideable clutch 107.

Between the two shafts 100 and 101 is a first 6 variable speed ratio unit in the form of an adjustable eccentric slide crank, comprising a 5 slotted crank disc 108 fixed to the end of the shaft, and a crank arm 110 fixed to the opposed end of the shaft 101, and carrying a crank wrist roller slideable in the slot of said disc.

Between the two shafts 101 and 102 is a spur 6 gear transmission 112 and 113 with a 1 to 1 speed ratio, and between the two shafts 102 and 53 is a second variable speed ratio unit in the form of an adjustable eccentric slide crank, comprising a slotted crank disc 114 on shaft 102, and crank 6 arm 115 on the other shaft 53 with slideable crank wrist connections to said disc.

The eccentricity of the two crank connections 7 is adjustable according to the desired total time cycle of said mechanism, and desirably by a 7 single adjusting mechanism, which does not interfere with the transmission between the two shafts 101 and 102. For that purpose, these shafts are journalled in a crank bearing block 116, movable by an adjusting screw 117. The eccen- 7

tricity of these two crank units can be adjusted simultaneously to a minimum extent, to impart the desired maximum angular velocity to the output shaft 53 for a 1 to 1 drive through the power transmission, or adjusted to a maximum extent to impart the same maximum angular velocity to said shaft in the same phase for a 1 to 2 drive. For instance, when it is desired to feed one sheet for every revolution of the slotting heads 37, the clutch 107 is shifted to couple the gears 104 to the shaft 100, and the eccentricity of the two crank units adjusted to a minimum extent by the adjustment of the block 116, so that the speed ratio of each crank unit at maximum velocity phase of the output shaft 53 will be 1 to 1.32. With this 1 to 1 setting of the speed change gearing, the drive to the output shaft 53 will be through the gears 103 and 104, the first crank unit 108 and 110, gears 112 and 113, and through the second crank unit 114 and 115, and the speed ratio between input shaft 50 and output shaft 53 in maximum velocity phase of said latter shaft will be 1 to 1.76.

When it is desired to feed one sheet for every two revolutions of the slotting heads, the clutch 107 is shifted to couple the gear 106 to the shaft 100, and the eccentricity of the two crank units adjusted to a maximum extent indicated approximately by the position F in dotted lines, so that the speed ratio of each crank unit will be 1 to 1.87. With this setting of the speed change gearing, the drive to the output shaft 53 will be through the gears 105, 106 at a 1 to 2 speed ratio, through the first crank unit 108, 110, gears 112, 113, and through the second crank unit 114, 115, and the speed ratio between the input shaft 50 and the output shaft 53 in maximum velocity phase of the latter shaft will be 1 to 1.76, this being equal to the speed ratio with a 1 to 1 drive. 40 This maximum velocity of the output shaft will occur in the same portion of its cycle in both settings of the speed change gearing.

The eccentric adjustment of the crank units between the two extremes indicated does not in any way affect the length of the connection between the output shaft 53 and the feed lever 15.

Fig. 12 is diagrammatic, and not intended to show the actual position and phases of the slide crank units with respect to connecting rod 21. 50 For instance, in actual construction, the adjusting screw 117 extends substantially vertically, and when the driving and driven elements of each slide crank unit are in phase for maximum speed ratio therebetween, the crank 56 extends downwardly. It should also be noted, that the bearing block for shaft 53 is stationary, and therefore any adjustment of bearing block 116 through screw 117 will not affect the length of the connecting rod 21.

Fig. 13 shows diagrammatically another form of sheet feeding power transmission comprising the input shaft 50, output shaft 53, and an intermediate shaft 100, and a speed change gearing between shafts 50 and 100 similar to that of Fig. 12.

Between the two shafts 53 and 100 is a variable speed ratio unit in the form of an eccentric slide crank 120, similar to that of Fig. 12, adjustable by means of a crank bearing block 122, and an adjusting screw 123. The eccentricity of this crank unit 120 is adjusted to impart a maximum speed ratio of 1 to 1.76 between the input and output side thereof at the maximum velocity phase of the output shaft 53, or a maximum speed ratio of 1 to 3.52 at the same phase. When

it is desired to feed one sheet per revolution of the slotting heads 37, the clutch 107 is moved in position to couple the gear 104 to the shaft 100, and the crank unit is adjusted to obtain the ratio of 1 to 1.76 above referred to at the maximum velocity phase of said latter shaft.

When it is desired to feed one sheet for every two revolutions of the slotting head, the clutch is moved in an opposite direction to couple the gear 106 to the shaft 100, and the crank unit is adjusted to obtain a ratio of 1 to 3.52 in the maximum velocity phase of the output shaft, so that the velocity of said output shaft at that phase will be the same as it was with a 1 to 1 setting.

Figs. 14 and 15 show another form of sheet feeding mechanism comprising input shaft 50, output shaft 53, and a pair of intermediate shafts 130 and 131 parallel to said shafts 50 and 53. 20 Fixed to the shaft 50 is a gear 132, meshing with a gear 133 fixed to the shaft 130, the speed ratio between said gears being 4 to 1. Between the shaft 53 and the gear 133 is a speed change gearing, including two pairs of intermeshing gears, one pair comprising gears 134 and 135 in 4 to 1 speed ratio, and the other pair comprising gears 136 and 137 also in the 4 to 1 speed ratio. The gears 135 and 137 are fixed to the shaft 131, while gears 134 and 136 are loosely mounted on shaft 53, and selectively coupled thereto by a slideable clutch 138. Between the two shafts 130 and 131 are two Geneva gear units, forming part of the speed change gearing. One of these Geneva gear units comprises cross gear 140, mounted on the inner face of the gear 135 for rotation therewith, and driven from four driving pins 141, affixed to one side of the gear 133 in quadrant relationship. Also on this side of the gear 133 is the usual locking member 142 for cooperation with the cross gear 140. The other Geneva gear unit 30 comprises cross gear 143, similar to gear 140, and mounted on the inner face of the gear 137 for rotation therewith, said gear 143 being driven from two driving pins 144 extending from the other side of gear 133, and diametrically arranged in 45 respective alignment with two of the pins 141. On one side of the gear 133 is the usual locking member for cooperation with the cross gear 143.

When it is desired to feed one sheet for every revolution of the slotting heads, the clutch 138 50 is moved into position to lock the gear 134 to the output shaft 53. With this setting of the speed change gearing, the transmission between the input and output shafts will be through gears 132 and 133, pins 141, cross gear 140, and gears 55 135 and 134. Since there are four driving pins 141 cooperating with this cross gear 140, said pins will cause the gear 134 to rotate through four identical revolutions, each at varying speed for each turn of the gear 135, so that the output shaft 53 will rotate one revolution at varying speed for every revolution of the input shaft 50 at constant speed.

When it is desired to feed one sheet for every two revolutions of the slotting head, the clutch 65 member 138 is moved into position to lock the gear 136 to the output shaft 53. With this setting of the speed change gearing, the transmission will be through the gears 132 and 133, pins 144, cross gear 143, and gears 137 and 136. Since 70 this Geneva unit has two driving pins 144, said pins will cause rotation of the gear 136 through one revolution at varying speed, during the first quarter revolution of the gear 133 carrying these pins. During the second quarter revolution of 75

this gear 133, the gear 136 will be held stationary. During the third quarter revolution, the gear 136 will again rotate through a varying speed cycle, and during the fourth revolution, this 5 gear will again be held stationary.

With either speed change setting, the cycles of operation of the reciprocating feed mechanism will be the same. In one setting however, the 10 cycles of operation of said feed mechanism repeat themselves in correspondence with the repeated revolutions of the slotting head, while in the other setting, the feed mechanism is stationary during alternate revolutions of said head.

Figs. 16 and 17 show another form of sheet 15 feeding transmission, in which the speed change gearing may be set to hold the reciprocating feed mechanism stationary during alternate revolutions of the slotting head. This transmission includes input shaft 50, output shaft 53, a third 20 shaft 150 parallel to said shafts 50 and 53, and a gearing between the shafts 53 and 150 for changing the frequency of operation of said shaft 53. This gearing includes two pairs of intermeshing gears, one pair comprising standard 25 spur gears 151 and 152 having a 1 to 2 speed ratio, the other pair comprising a mutilated spur gear 153 and a spur gear 154, said latter gears having a 1 to 2 speed ratio between intermeshing parts thereof, and said gear 154 having a portion 30 157 with teeth omitted, to lock said gear 154 against rotation in predetermined rotative position when not meshing with gear 153, and to assure proper intermeshing of said gears 153 and 154 at the beginning of the intermeshing 35 phase. The gears 151 and 153 are affixed to the shaft 150, while gears 152 and 154 are loose on shaft 50, but selectively coupled thereto by a slide clutch 155. The shaft 150 is driven from the shaft 50 through a gear 156 meshing with the gear 151, the speed ratio between said gears 40 being 2 to 1.

The teeth on the mutilated gear 153 extend substantially along one-half of the periphery thereof, and are shown in Fig. 17 on the upper 45 half of said gear.

For a feed of one sheet for every revolution of the slotting heads 37, the drive will be through gears 156, 151, and 152 to the output shaft 53. For a feed of one sheet for every two revolutions 50 of the slotting head, the drive will be through gears 156, 151, shaft 150, mutilated gear 153 and gear 154. In both settings of the transmission, the output shaft 53 will rotate at the same speed. However, with a 1 to 2 feed, during the time the 55 teeth parts of the two gears 153 and 154 are intermeshed, the gear 154 makes one complete revolution, and during the remainder of the revolution of said gear 153, the gear 154 is stationary.

In the construction shown in Figs. 16 and 17, 60 there is no variable speed ratio unit, so that variations in speed of the feed mechanism during its cycle are attained only through the crank and rod connections 56 and 21. This is not entirely satisfactory, since it would be necessary to increase the length of the crank, and therefore the 65 length of the stroke of feed bar 14 (see Fig. 1), to obtain the same feeding velocity as with an elliptical gear drive or its equivalent. A shorter stroke allows for a shorter minimum sheet length 70 to be fed into the machine. It is desirable therefore to provide a variable speed ratio unit to attain the desired rate of variation in the speed of the feed mechanism during each of its cycles. In the construction of Figs. 1 to 15, this desired 75 variation is obtained through elliptical gears,

variable throw cranks or Geneva movements as already described. In the construction of Figs. 16 and 17, such a variable ratio speed unit preferably in the form of elliptical gears may be provided at the inlet side of the input shaft 50. 5

In all of the forms of construction shown, there is provided a power transmission mechanism with a speed change gearing for changing the frequency of operation of the reciprocating feed parts, without changing the speed of said parts at a 10 definite portion of their cycle.

In the constructions of Figs. 1 to 13, this change in frequency is obtained by changing the total time cycle of the feeding mechanism, so that it takes two revolutions of the slotting head to 15 complete one stroke of the feeding mechanism.

In the constructions of Figs. 14 to 17 however, the change in frequency is obtained by holding the feeding mechanism stationary during alternate revolutions of the slotting head, the cycles 20 of each stroke for both settings of the speed change gearing being identical.

As many changes could be made in the above construction, and many apparently widely different embodiments of this invention could be made 25 without departing from the scope thereof, it is intended that all matter contained in the above description or shown in the accompanying drawings shall be interpreted as illustrative and not in a 30 limiting sense.

Having thus described my invention, what I claim as new and desire to secure by Letters Patent is:

1. A machine for making box blanks, including 35 a reciprocable feeding mechanism for feeding stiff sheets successively from a stack, and a power transmission mechanism for operating said feeding mechanism, including means for changing the frequency of operation of said feeding mechanism, and means for maintaining the speed of 40 said feeding mechanism in a given portion of its cycle substantially the same regardless of changes in said frequency.

2. In a machine for making box blanks where- 45 in there is provided a rotatable member for operating on sheets of stiff material, and a reciprocable feeding mechanism for feeding sheets successively from a stack, a power transmission mechanism for operating said feeding mechanism, including an input shaft, an output shaft, 50 means connecting said output shaft and said feeding mechanism for operating said feeding mechanism, a speed change gearing for changing the frequency of operation of said output shaft with respect to said input shaft to change the 55 frequency of operation of said feeding mechanism, and means for maintaining the speed of said feeding mechanism in a given portion of its cycle substantially the same regardless of changes in said frequency.

3. A machine for making box blanks from 60 sheets of stiff material, having a slotting head, a pair of feed rolls, a reciprocable feeding mechanism for feeding sheets successively from a stack to said feed rolls, and a power transmission mechanism for operating said feeding mechanism, including means for changing the frequency of operation of said feeding mechanism, and means for maintaining the speed of said feeding mechanism, in that portion of its forward stroke at 65 which the forward edge of the sheet being fed is substantially in the nip portion of said feed rolls, substantially equal to the peripheral speed of said feed rolls, regardless of changes in said frequency. 70

4. A machine for making box blanks from sheets of stiff material, including a rotatable member for operating on said sheets, a reciprocable feeding mechanism for feeding said sheets successively from a stack, a power transmission mechanism for operating said feeding mechanism, including a speed change gearing for changing the frequency of operation of said feeding mechanism, so that said latter mechanism will effect a complete feeding cycle for every one or two revolutions of said member according to the setting of said speed change gearing, and means for maintaining the speed of said speed change mechanism in a given portion of its cycle the same with either setting of the speed change gearing. 5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940
- means for reciprocating said feeding mechanism at a variable speed, and at a maximum speed at the phase of its forward stroke when the forward edge of the sheet being fed is substantially at the nip portion of said feed rolls, said maximum speed being substantially equal to the peripheral speed of said feed rolls, and means for changing the frequency of operation of said feeding mechanism without changing the maximum speed of said mechanism at said portion of its forward stroke. 5 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940
9. A machine for making box blanks, including a rotatable member for operating on stiff sheets to make said blanks, a reciprocable feeding mechanism for feeding sheets successively from a stack, a power transmission mechanism for operating said feeding mechanism, including means for changing the total time cycle of operation of said feeding mechanism, and means for maintaining the speed of said feeding mechanism in a given portion of its cycle the same, regardless of changes in said frequency. 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940
10. A machine for making box blanks, including a slotting head for operating on stiff sheets to make said box blanks, a pair of feed rolls, and a feeding mechanism for feeding said sheets successively from a stack towards said feed rolls, a power transmission mechanism for operating said feeding mechanism, including a speed change gearing for changing the total time cycle of operation of said feeding mechanism, so that the period of each stroke thereof is equal to or twice the period of revolution of said slotting head, in accordance with the setting of said speed change gearing, and means for maintaining the speed of said feeding mechanism, in that portion of its cycle wherein the forward edge of the sheet being fed is substantially in the nip portion of the feed rolls, the same and equal to the peripheral speed of said feed rolls with either setting of the speed change gearing. 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940
11. A machine for making box blanks, including a slotting head for operating on stiff sheets to make said box blanks, a pair of feed rolls, and a feeding mechanism for feeding said sheets successively from a stack towards said feed rolls, and a power transmission mechanism for operating said feeding mechanism, including a speed change gearing for changing the total time cycle of operation of said feeding mechanism, so that the period of each stroke thereof is equal to or twice the period of revolution of said slotting head, in accordance with the setting of said speed change gearing. 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940
12. A machine for making box blanks from sheets of stiff material, including a rotatable member for operating on said sheets, a reciprocable feeding mechanism for feeding said sheets successively from a stack, a power transmission mechanism for operating said feeding mechanism, including means for operating said feeding mechanism selectively through recurrent cycles at a given frequency, or intermittently through similar cycles at a less frequency, and means for maintaining the speed of said feeding mechanism in a given portion of its cycle the same regardless of changes in said frequency. 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940
13. A printer slotter for making box blanks, including feed rolls, a printing cylinder, a slotting head, a knocker feed for delivering the sheets from a stack to said feed rolls, a drive shaft for operating said feed rolls, printing cylinder, and slotting head with the same peripheral speed, and connections between said shaft and said knocker feed, and selectively operable to deliver a sheet 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

for each revolution or each alternate revolution of said cylinder head.

14. A printer slotter for making box blanks, including feed rolls, a printing cylinder, a slotting head, a knocker feed for delivering the sheets from a stack to said feed rolls, a drive shaft for operating said feed rolls, printing cylinder, and slotting head with the same peripheral speed, and

connections between said shaft and said knocker feed, and selectively operable to deliver a sheet for each revolution or each alternate revolution of said cylinder head, the speed of the sheet at the instant it enters the feed rolls being the same as the peripheral speed of the latter in either frequency of sheet delivery. 5

KARL SIEG.
